UNITED STATES PATENT OFFICE.

JOSEPH GIBBONS HILL, OF FLATBUSH, NEW YORK.

CAR-WHEEL.

SPECIFICATION forming part of Letters Patent No. 350,133, dated October 5, 1886.

Application filed December 14, 1885. Serial No. 185,632. (No model.)

To all whom it may concern:

Be it known that I, JOSEPH GIBBONS HILL, a citizen of the United States, residing at Flat-
5 bush, in the county of Kings and State of New York, have invented new and useful Improve-
ments in Car-Wheels, of which the following is a specification.

My invention relates to the construction of car-wheels, and the purpose thereof is to im-
10 part to such wheels a natural elasticity and a high degree of safety, and to effect increased economy in production, the same being the products of the novel construction which constitutes the subject-matter of this application.

15 The invention consists in the several novel features of construction and combinations of parts hereinafter fully set forth, and definitely pointed out in the claims annexed to this specification.

20 Referring to the accompanying drawings, Figure 1 is an elevation of the complete wheel. Fig. 2 is a central vertical section in the axial line of the wheel. Fig. 3 is an elevation of the parts composing the wheel slightly separated. Fig. 4 is central vertical section of the parts composing the wheel slightly removed from each other to show the construction.

In the said drawings, the reference-numeral 1 designates the rim of the wheel, which is cast 20 or rolled, and is provided with the flange 2 and an interior shoulder or flange, 3, which is located centrally on the inner face of the annular rim. The separate hub 4 may be formed by casting, or it may be struck up in a die. It 35 is provided with a circumferential flange or shoulder, 5, and a central opening, 6^a, for the axle.

The numeral 6 denotes the web-plates, which consist of two annular pieces, preferably 40 wrought, though they may be formed in other ways. Each of these plates has an external diameter equal, or substantially so, to the internal dimension of the rim, and is provided with a central opening, 7, of such size that it closely 45 embraces the hub portion 4.

The annular plates 6 are each curved or bent outwardly at a point between the hub and the rim of the wheel, the curve formed being annular relatively to the plate, and in cross-sec- 50 tion approximating the form of a semi-ellipse, as shown at 8, and the curved portion in each being substantially opposite that of the other.

Above and below the annular curved portion 8 is an annular flat portion, 9, adapted to lie against the flanges or shoulders 3 and 5 upon the rim and hub, respectively. 55

The parts are assembled and united by means of bolts 10, passing through perforations 11 in the outer flat portions, 9, and through similar openings in the interior flange, 3. The inner 60 edges of the annular plates are in like manner secured to the circumferential flange 5 upon the hub, the finished wheel being shown in Figs. 1 and 2.

Heretofore corrugated plates have been used 65 in the construction of car-wheels; but in employing plates having annular corrugation of this kind the rim and hub have both been cast upon the previously-corrugated plates, and the shrinkage of the rim as it cooled has invariably produced either a dangerous weakness or a positive break. The impossibility, more- 70 over, of securing anything like uniform results in such a mode of construction, even had success been possible, has caused this construction to be generally condemned. In cases where the corrugations have been radial an increased 75 rigidity has been the result, whereas it is the principal object of inventors to promote and increase the elasticity of the parts. 80

By my invention I not only provide a wheel having a high degree of elasticity and possessing great strength, but I materially decrease the cost of manufacture, which is a considera- 85 tion of the highest importance.

I do not broadly claim a separate or particu- 90 lar rim or a separate or particular hub or corrugated plates, but the particular construction and combination of the parts hereinbefore described and shown, whereby elasticity is pro- 95 vided and a greater degree of safety is secured.

The essential features comprising my inven- 100 tion reside not specially in the fact that the rim has an exterior side flange, but in the fact that I provide a structure which is new as a whole and comprises a rim having a single central inwardly-projecting annular flange, a hub formed centrally between its ends with an outwardly-projecting flange, web-plates formed with annular curves semi-elliptic in cross-section, said plates being seated on the hub and bearing, respectively, against the opposite sides of the said two flanges, and bolts, each one of which passes through both web-plates to se-

cure them to the flanges. This construction and combination insures strength and safety and provides the requisite elasticity, and differs substantially from a wheel for agricultural implements comprising a rim with an annular inwardly-projecting flange at or adjacent to each edge, a hub having an outwardly-projecting annular flange adjacent to each end, and two corrugated sheet-metal disks seated on the hub and bolted, respectively, to the flanges on the hub and the flanges on the rim. Such a wheel may be useful as a drive-wheel for agricultural implements; but it lacks the solidity, compactness, and substantial qualities that are requisite in a supporting-wheel for railway cars.

What I claim is—

1. A railway-car wheel consisting of the rim 1, having the inwardly-projecting annular flange 3 formed centrally on its inner face, the hub 4, formed with the central annular flange 5, and the web-plates 6, each formed with annular curves semi-elliptic in cross-section, said plates being secured at their inner edges directly to the opposite faces of the single cen-

tral hub-flange 5, and at their outer edges directly to the opposite faces of the single central rim-flange 3, substantially as described.

2. A railway-car - wheel consisting of the rim 1, provided with the exterior annular side flange, 2, and having the single inwardly-projecting annular flange 3 formed centrally on its inner face, the hub 4, formed with the single central annular flange 5, the web - plates 6, each formed with annular curves semi-elliptic 35 in cross-section, and having their inner edges abutting directly against the opposite faces of the single central hub-flange and their outer edges abutting directly against the opposite faces of the single central rim-flange, and bolts 40 10, each passing through both web-plates and attaching them to the said central flanges, substantially as described.

In testimony whereof I affix my signature in presence of two witnesses.

JOSEPH GIBBONS HILL.
